(57) **CLAIM**

The ornamental design for a hot comb hair straightener, as shown and described.

DESCRIPTION

FIG. 1 is a front and top perspective view of a hot comb hair straightener showing my design according to a first embodiment;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan the view thereof;

FIG. 8 is a bottom plan the view thereof;

FIG. 9 is a front perspective view thereof, showing the hot comb straightener with an accessory attachment;

FIG. 10 is a front and top perspective view of a hot comb hair straightener showing my design according to a second embodiment;

FIG. 11 is a rear and bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan the view thereof;

FIG. 17 is a bottom plan the view thereof; and,

FIG. 18 is a front perspective view thereof, showing the hot comb straightener with an accessory attachment.

The broken line accessory attachments illustrate the environment of the hair comb hair straightener and the remaining broken lines illustrate portions of the hair comb hair straightener. The broken line disclosures form no part of the claimed design.
